UNITED STATES PATENT OFFICE.

JULIUS BERBECKER, OF NEW YORK, N. Y.

LAMBREQUIN-PIN.

SPECIFICATION forming part of Letters Patent No. 323,259, dated July 28, 1885.

Application filed March 6, 1885. (No model.)

To all whom it may concern:

Be it known that I, JULIUS BERBECKER, of the city, county, and State of New York, have invented certain new and useful Improvements 5 in Lambrequin-Pins, of which the following is a specification.

This invention has reference to an improved pin for quickly and conveniently suspending lambrequins, curtains, and the like from curtain-pole rings; and the invention consists of 10 a lambrequin-pin made of a main plate having a downwardly-bent hook at its upper end and a sleeve at the lower end, to which a U-shaped fastening-pin is hinged the ends of 15 which are retained by guards at the upper part of the main plate.

In the accompanying drawings, Figure 1 represents a front view of my improved lambrequin-pin, shown as suspended from the eye 20 of a curtain-pole ring; and Fig. 2 is a vertical transverse section of the same.

Similar letters of reference indicate corresponding parts.

A in the drawings represents the body or 25 main plate of my improved lambrequin-pin, which is provided at its upper end with a downwardly-bent hook, B, that is passed through the eye a at the lower part of a curtain-pole ring, C. The hook B is made con- 30 cavo-convex or corrugated to impart additional strength to the same. The lower end of the main plate A is bent up, so as to form a sleeve, b, to which a U-shaped fastening- 35 pin, C, is hinged. The ends of the fastening- pin C are retained by forwardly-bent front guards, d d, which, like the hook B and sleeve b, are made integral with the main plate A. By pressing the ends of the pin C toward each 40 other they can be readily released from the guards, and thereby the pin moved in a downward direction, as shown in dotted lines in

Fig. 2. The ends of the pin C' are passed through the lambrequin or curtain at some distance below its edge, after which the pin is moved up, pressed together, and retained by 45 the guard d d.

My improved lambrequin-pin has the advantage that the lambrequin or curtain can be suspended close to the eye of the curtain-pole rings, so that the pin is almost entirely cov- 50 ered and out of sight. The lambrequin or curtain is retained in a secure manner by the pins, which are less liable to get detached from the eyes of the rings than the wire pins heretofore in use.

I am aware that garment-clasps have been provided with a pin attachment hinged to the lower plate of the clasp and retained thereon by ears, and I do not claim this feature. I am also aware that hooks for eye-glass holders 60 have been made of sheet-metal hooks combined with safety-pins, and I therefore do not claim these features broadly.

Having thus described my invention, I claim as new and desire to secure by Letters Patent— 65

A lambrequin-pin composed of a main plate having a downwardly-bent rear hook at the upper end, a bent-up sleeve at the lower end, and forward-bent guards at the upper end of the plate, said hook, sleeve, and guards being 70 made integral with the main plate, and of a U-shaped fastening-pin hinged to the sleeve and adapted to be retained by the guards, sub- stantially as set forth.

In testimony that I claim the foregoing as 75 my invention I have signed my name in presence of two subscribing witnesses.

JULIUS BERBECKER.
